United States Patent Office

Des. 183,595
Patented Sept. 30, 1958

183,595

RECORD HOLDER OR SIMILAR ARTICLE

Charles L. Borskey, Houston, Tex.

Application July 10, 1957, Serial No. 46,891

Term of patent 7 years

(Cl. D33—3)

Fig. 1

Fig. 2

Fig. 1 is a front perspective view of a record holder or similar article, showing my new design. The dotted line indication of a record is for illustrative purposes only.

Fig. 2 is a rear perspective view showing the underside thereof.

I claim:

The ornamental design for a record holder or similar article, as shown and described.
